UNITED STATES PATENT OFFICE

MAX M. SUPPES, OF ELYRIA, OHIO, ASSIGNOR TO THE FOX FURNACE COMPANY, OF ELYRIA, OHIO, A CORPORATION OF OHIO

HEATING APPARATUS

Application filed November 13, 1930. Serial No. 495,411.

My invention relates to new and useful improvements in heating apparatus, and more particularly to an air heating furnace of the type employed to heat air to be supplied to the rooms of a dwelling, or the like.

An object of my invention is to provide a furnace in which the furnace chamber is sealed with respect to the air heating space so as to prevent any passage of gases from the furnace chamber into the air heating space.

Another object is to provide a furnace in which leakage of gases, or the like, from the furnace chamber will be visible so that the leak may be readily detected and sealed.

The invention consists in the improved construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

25 Figure 1 is a view in front elevation of a furnace embodying my invention, but having the top of the jacket removed;

Fig. 2 is a side view, in perspective, of the furnace with the jacket removed;

30 Fig. 3 is a view in side elevation, and partly in vertical section, on the line 3—3 of Fig. 1;

Fig. 4 is a top plan view of the furnace casing with parts broken away to show the construction, and

35 Fig. 5 is a detail view in section on the line 5—5 of Fig. 1.

Referring to the drawings by characters of reference, 1 designates a furnace casing comprising a drum member 2 and a pouch 3, which are preferably of sheet metal, such as steel. The drum member 2 encloses the combustion chamber 4, the fire-pot 5 and the ash-pit 6, and has an upper portion or head member 7 and a lower portion or body member 8 which are preferably substantially cylindrical, the head member 7 having a top wall 9 and a depending cylindrical wall 10 which overlaps the top edge of the body member 8, and is sealed thereto, preferably by a welded joint. Adjacent the lower, front edge

of the wall 10 is a forwardly extending portion or plate member 11 which is preferably inclined slightly downward, and which forms the top wall of the pouch 3. The side edges of the member 11 diverge forwardly and have 55 depending flanges 12, 13, which at their rear ends merge into the wall 10 and which overlap and are sealed, preferably by a welded joint, to the top edges of side wing or wall members 14, 15, respectively, which extend forwardly in diverging relation from the body member 8, and which form the side walls of the pouch 3. The head member 7 and member 11 with flanges 12, 13, are preferably formed from a single blank of sheet metal. The body member 8 and members 14, 15 are also preferably formed from a single blank of sheet metal. The members 14, 15 extend to the bottom of the body member 8 and form the side walls of the fuel charging 60 space 16 and of the ash-pit extension 17. The members 11, 14 and 15 terminate forwardly in a substantially common vertical plane and have rigidly secured and sealed thereto, preferably by welding, a frame 18 65 having side members 19, 20 and a top cross member 21. The members 14, 15 join the frame side members 19, 20, respectively, intermediate their side edges, and member 11 joins frame top member 21 intermediate its 70 top and bottom edges, so that the pouch 3 has along its side and top front edges a laterally, inward extending flange 22 and a laterally, outward extending flange 23. The casing 1 has a bottom wall 24 forming the 75 floor of the ash-pit and ash-pit extension, and having its periphery sealed and rigidly secured, as by welding, to the body member 8 and the wing members 14, 15, and terminating at its front edge substantially in the 80 plane of the front face of frame 18. The body member 8 has an open front defined by the portion 11, members 14, 15, and wall 24. Closing the front of the casing 1 and body member 8 is a front furnace wall 25, preferably of cast metal, and having upper and lower plate members 26, 27, which are joined and sealed together along a substantially horizontal line. The upper plate member 26, at its bottom edge, overlaps the front top 85

90

95

100

edge of member 27, the member 26 having its lower marginal edge portion offset, as at 28, to permit the members 26, 27 to lie in a substantially common plane. The front face portion of member 27 which lies behind member 26, has a recess or channel 29 therein in which is positioned packing material such as asbestos rope. The members 26 and 27 are clamped together and upon the packing material by nuts and bolts 30 passed through the members below the recess 29. The front wall 25 has in its rear face and adjacent its side and top edges a continuous channel or recess 31 which overlies the flange 22, and in which is positioned joint sealing material 32, such as asbestos rope packing, or the like, see Fig. 5. The wall 25 is rigidly secured to the casing 1 by nuts and bolts 33 passed through the edges of members 26, 27 outside 20 of the recess 31 and through the flange 22. Through the wall members 26, 27 are fire-door and ash-pit door openings 34, 35, respectively, the opening 34 registering with the fuel charging throat 16, which has a bottom wall formed by a plate member 36 bridging the space between the wall 25 and the fire-pot 5. Within the casing 1 is a grate member 37 positioned at the bottom of the fire-pot 5, and which may be of any well known construction. In the rear wall of the combustion chamber 4 is an opening in which is rigidly secured and sealed, as by welding, an outlet flue 38 for the products of combustion, and which connects, preferably by a 35 welded joint, into a sheet metal radiator 39, also preferably having welded joints. Secured to the side frame members 19, 20 are corner posts 40, 41 having bolts 42 extending through the flange 23, with the inside edges of the posts spaced from the side edges of the wall 25, as at 43, to form vertical channels.

The furnace casing 1 and radiator 39 comprise a heating unit which is enclosed within 45 a jacket or outer casing 44, which is spaced from the unit to provide an air heating chamber. The jacket 44 seats on a base ring 45 which terminates at the corner posts 40, 41, and has a front opening, the upper part of 50 which is closed by a front jacket member 46 which extends laterally to the outside edges of and seats upon the corner posts 40, 41. The side edges of the jacket at its front opening are bolted, as at 47, or otherwise 55 secured to the corner posts and to the side edges of the member 46. The lower edge of the member 46 which is preferably of cast metal to support a humidifier pan 48, overlaps the frame cross member 21 in vertically spaced relation to the top edge of 60 the wall member 26 to form a continuation of the channels 43, as at 43^a, and is secured by bolts 49, or the like, to the flange 23. The member 46 may be sealed to the frame 18 by 65 packing material positioned in a recess 50

formed in the rear face of member 46 at its lower edge and clamped against frame 18 by the bolts 49. The jacket is provided with apertures for the passage of the smoke outlet pipes 51, 52, which lead from the radiator 39, the pipes preferably being welded to the radiator.

It will thus be seen that due to the joints of the furnace casing 1 and the radiator 39 which are within the jacket 44 being welded, there can be no leakage from the casing into the air heating space within the jacket. Should any leak occur at the joint between the front wall 25 and the casing 1, the leaking gas, dust or oil would pass into the channel 43 and thence into the room or space around the furnace and not into the air heating space, as the joint does not communicate with the interior of the jacket. Since any leakage from the casing 1 must pass into the channel 43, 43^a, the leak may be readily detected and easily sealed by merely loosening certain of the bolts 33, inserting cement, and then tightening the bolts.

What I claim and desire to secure by Letters Patent of the United States is:—

1. A hot air furnace, comprising a casing having a front opening, a frame sealed to said casing around said opening, a front furnace wall rigidly secured at its top and side edges to said frame, and a jacket enclosing said casing and secured to said frame in spaced relation to said wall whereby the joint between said wall and said frame is out of communication with the space within said jacket.

2. A hot air furnace, comprising a casing having a front opening, a frame sealed to said casing around said opening, a front furnace wall overlying the front face of and rigidly secured at its top and side edges to said frame, and a jacket enclosing said casing and secured to the front face of said frame in spaced relation to said wall whereby the joint between said wall and said frame is out of communication with the space within said jacket.

3. A hot air furnace, comprising a casing having a front opening, a frame sealed to said casing around said opening, a front furnace wall rigidly secured at its top and side edges to said frame, corner posts secured to the sides of said frame in spaced relation to the side edges of said wall, and a jacket enclosing said casing and having a front opening, said jacket being secured at the sides of its opening to said posts and being secured at the top of its opening to said frame in spaced relation to said wall.

4. A hot air furnace comprising a casing having an ash-pit and a fuel charging throat, said casing having forwardly extending side wall members extending from the bottom of the ash-pit to the top of the fuel charging throat and having adjacent its upper end a

plate member extending between and joined to said wall members, a front furnace wall secured and sealed along its side and top edges to said wall members and said plate member, and a jacket enclosing said casing and secured to said wall members and said plate member in spaced relation to said front furnace wall.

5. A hot air furnace comprising a casing 10 having an ash-pit and a fuel charging throat, said casing having forwardly extending side wall members extending from the bottom of the ash-pit to the top of the fuel charging throat and having adjacent its upper end a 15 plate member extending between and joined to said wall members, a frame on the front edges of said wall members and said plate member, a front furnace wall secured and sealed along its side and top edges to said 20 frame, and a jacket enclosing said casing and secured to said frame in spaced relation to said front furnace wall.

6. A hot air furnace comprising a casing having an ash-pit and a fuel charging throat, 25 said casing having forwardly extending side wall members extending from the bottom of the ash-pit to the top of the fuel charging throat and having adjacent its upper end a

plate member extending between and joined to said wall members, a frame on the front edges of said wall members and said plate member, a front furnace wall secured and sealed along its side and top edges to said 70 frame, corner posts secured to the sides of said frame in spaced relation to the side edges of said furnace wall, and a jacket enclosing said casing and secured to said posts.

7. A hot air furnace comprising a casing 75 having an ash-pit and a fuel charging throat, said casing having forwardly extending side wall members extending from the bottom of the ash-pit to the top of the fuel charging throat and having adjacent its upper end a 80 plate member extending between and joined at its side edges to said wall members, a frame on the front edges of said wall members and said plate member, a front furnace wall secured to said frame and having a recess in its rear face extending along its side and top edges and closed by said frame, packing 85 material in said recess to seal the joint, and a jacket enclosing said casing and secured to said frame.

In testimony whereof I have hereunto subscribed my name this 4th day of Nov., 1930.

MAX M. SUPPES.
